J. H. FOOTE

WEATHER STRIP

Filed Jan. 26, 1924

UNITED STATES PATENT OFFICE.

JAMES H. FOOTE, OF CINCINNATI, OHIO.

WEATHER STRIP.

Application filed January 26, 1924. Serial No. 688,638.

To all whom it may concern:

Be it known that I, JAMES H. FOOTE, a citizen of the United States, residing at Cincinnati, in the county of Hamilton and State of Ohio, have invented certain new and useful Improvements in Weather Strips, of which the following is a specification.

My invention relates to improvements in weatherstrip. One of its objects is to provide an improved weatherstrip adapted to be used to advantage upon house doors, refrigerator doors, casement windows, and for similar purposes. Another object is to provide an improved weatherstrip adapted to close the joints at the corners, as for instance to close the joints at the corners of refrigerator doors to prevent the escape of cold air when the refrigerator door is closed, or to render a casement window or a door weatherproof. Another object is to provide a reliable all metal weatherstrip adapted to close joints of the character above specified. Another object is to provide an improved weatherstrip actuated by or through the closing of the door or window sash to automatically actuate the weatherstrip to close the joints upon one or more sides of the door or sash. Another object is to provide an improved and more effective weatherproof joint. Another object is to provide a resilient weatherstrip for the above purposes adapted to retain its original shape and its original resiliency for long periods of time. My invention also comprises certain details of form and combination of components, all of which will be fully set forth in the description of the accompanying drawings, in which:

Fig. 1 is a vertical sectional diagram through the frame of a casement window with the sash open or omitted and with my improved weatherstrip in place thereon in idle position.

Fig. 2 is a view similar to Fig. 1 showing the window sash closed and the weatherstrip in active position closing the window joints.

Fig. 3 is a view similar to Fig. 1 through a door frame showing the door partly open and the weatherstrip in idle position.

Fig. 4 is a view similar to Fig. 3 showing

the door closed and the weatherstrip in active position to close the joints.

Fig. 5 is a perspective view of one of the lower corners of the door with the weatherstrip attached thereto. 55

Fig. 6 is a perspective view of one of the door weatherstrip members detached.

Fig. 7 is a diagram illustrating one manner in which the joints are closed at the corners of a door or window sash. 60

Fig. 8 is a sectional detail illustrating a modification of Figs. 1 and 2.

Fig. 9 is a sectional detail showing its application to an inwardly opening sash.

The accompanying drawings illustrate the preferred embodiments of my invention in Figs. 1 and 2 of which 16 represents the frame of a casement window and 16 represents the casement sash hinged to the window frame 15 and opening outwardly therefrom. To the top, bottom and opposite sides of the window frame are fastened sections of weatherstrip as shown in Fig. 1. 65

As shown in Fig. 1 the respective sections of weather strip are formed by bending or folding a strip of resilient sheet metal upon itself lengthwise of the strip at 17, and bending said folded strip into an angular cross-sectional pattern substantially as shown in Fig. 1. One edge 18 of the strip is 70 also preferably folded upon itself to provide a smooth finish or binding for said edge 18. The lip or section 19 of the weatherstrip is attached to the jamb or face 26 of the window frame at intervals by means of a series of screws or nails 20. The middle sections 21 and 22 of the weatherstrip rest one against the other and against the joint face 24 of the window frame. The weatherstrip section 25 is bent with reference to the section 22 so as to normally extend away from the section 19. At their meeting ends the sections 25 are preferably mitered so as to 75

respectively avoid interfering with the free movement or action of said sections 25. The inwardly projecting ends of the sections 21 and 22 may also be mitered if desired so as to barely contact with each other at their ends when the window sash is closed, but are preferably left the full length and re- 80

90

100

lied upon to close in upon the corner of the window sash from the dotted line position to the full line position Fig. 7, and to yield at 27 at their meeting faces outside of the window sash corner to effect close joints with the respective corners of the window sash or door substantially as shown in Fig. 7.

As the window sash 16 is closed into the window frame as shown in Fig. 2, the face 28 of the sash first contacts with the edge 18 of the weatherstrip section 25, and serves to firmly press the sections 25 toward and against the section 19 until the window sash reaches its full closed position and is latched shut thereby effecting a close and resilient and weather proof joint between the section 25 and the face 28 of the window sash.

Pressure by the window sash against the weatherstrip section 25 due to the confined position of the weatherstrip causes the apex of angle 30 of the weatherstrip to act as a pivotal point or fulcrum upon which the sections 25 and 22 turn or rock thereby forcing the edge 17 of the section 22 away from the face 24 of the window frame and against the edge or face 32 of the window sash to form a resilient and weatherproof joint between said section 22 and the face 32 of the window sash upon the four faces of said window sash. The edges of the sections 21 and 22 being united at 17, causes the section 21 to be also drawn away from the face 24 of the window frame together with the section 22. The section 19 being held with a close joint to the window frame, and the sections 25 and 22 being held resiliently in close contact with the faces 28 and 32 of the window sash, whereby I am enabled to secure and maintain a thoroughly effective wind and waterproof joint applicable to door or casement windows.

In Figs. 3, 4, 5 and 6, I have illustrated a modification adapted for use in connection with a door having a threshold strip 34 disposed beneath the bottom thereof. For such doors, strips 35, corresponding to the strip shown in Figs. 1 and 2 are attached to the top and both sides of the door frame 41 and adapted to be engaged by the door 420 when the door is closed in substantially the manner heretofore described in Figs. 1 and 2. To the bottom of the door is attached by means of screws or nails 36 a resilient sheet metal strip member 37 which is folded upon itself at 38. The sections 39 and 40 of the strip member 37 have embraced or held between them a strip member 42, preferably of resilient sheet metal of slightly heavier gauge than the strip member 37. The strip member 42 comprises a section 43 embraced between the sections 39 and 40, and a section 44 projecting downwardly from the door, at an angle so as to

be engaged by the threshold strip 34 when the door is brought to closed position. The free end of the strip section 40 is preferably extended along the lower face of section 44 and its lower edge 49 bent upwardly over the lower edge of the section 44 to assist in holding the strip member 42, 43, 44 in place with reference to the strip member 37, and also to provide a smooth finish or binding for the lower edge of the section 44. Opposite ends 45 and 46 of the section 43 are turned upwardly and enter recesses 47 cut in opposite edges of the lower end of the door. I also preferably provide metal face plates 48 outside of the end sections 45 and 46, which face plates are rigidly attached to the edges of the door at the bottom thereof.

While the door is in open position the strip members 37 and 42 due to their resiliency assume substantially the position shown in Fig. 3. When the door is closed the lower edge 49 and the lower edge of section 44 encased therein contact with the raised portion of the threshold strip 34 thereby causing the apex of angle 50 at the junction of the sections 43 and 44 to act as a fulcrum on which the sections 39 and 40 and also the sections 43 and 44 rock relative to the door, causing the strip sections 39, 40, 43, 44 to assume substantially the position shown in Fig. 4, in which the edges 38 and 49 are resiliently engaged with the upper face of the threshold strip 34 with sufficient tension to effectually close the joint between the lower edge of the door and the upper face of the threshold member 34. Ordinarily the resilient engagement at the edges 38 and 49 is sufficient to spring the metal and thereby somewhat increase the distance between the edges 38 and 49 above normal which tends to yieldingly keep the joint between the door and threshold member closed. The sections 45 and 46 move into and out of their housing recesses 47 to enable the strip member 42 to rock upon its fulcrum. The strips 35 at opposite sides of the door are designed to close in upon the outer faces of the face plates 48 to secure tight joints with the lower ends of the side edges of the door without interfering with the action of the strip across the bottom of the door. If desired the threshold strip 34 may be metal faced.

In Figure 8 I have illustrated a modification of my improved weatherstrip applicable substantially as described for Figs. 1 and 2 and comprising a strip member 52 of resilient sheet metal having a section 53 attached to a door or window frame 54 by means of screws or nails 55, and sections 56 and 57 located at an angle to section 53 and folded at 58 one upon the other. A strip member 59 preferably of resilient sheet metal and preferably of slightly heavier gauge than the strip member 52 comprises 130

a section 60 interposed between the sections 56 and 57 and a section 61 at an angle to the section 60. The section 61 of Fig. 8 corresponds to the section 25 of Fig. 1 and is adapted to be engaged by the door or window when closed and forced toward the section 53, which in turn causes the sections 56, 57 and 60 to move together upon the angle 64 serving as a fulcrum to cause the free edge 58 of section 57 to move toward and contact with the edge of the door or window to close the joint.

In Fig. 9 I have illustrated the application of my improved weatherstrip to close the joints where the sash of the casement window is hinged to open inwardly, and in which the operation is substantially the same as heretofore described for Figs. 1 and 2.

I also employ my improved weatherstrip by applying a portion of the strip-members to the door frame or window frame and another portion to the door or window sash, as for instance by applying two vertically positioned strip members to the opposite sides of the door frame or window frame and in connection therewith applying two horizontally positioned strip members one attached across the top and the other across the bottom of the door or window sash. The adjacent ends of the respective horizontal and vertical strip members are trimmed to pass each other without frictional engagement, but so as to close the joints at the corners with practically no open spaces. If desired strip members such as shown across the bottom of Figs. 3 and 4 with the recesses 47, projections 45 and 46, and face plates 48 may be employed also across the top of the door as well as across the bottom thereof.

The apparatus herein shown and described is capable of considerable modification within the scope of the claims without departing from the spirit of my invention.

What I claim is:

1. A weatherstrip of resilient material and of angular cross-section adapted to be attached to one joint forming member so as to have a rocking movement substantially upon the apex of the angle of said strip relative to the joint forming member to which it is attached, and to be engaged at both of the free ends of said angle by the opposite joint member when the joint is closed due to the rocking movement of said strip upon the apex of said angle.

2. A weatherstrip of resilient material and of angular cross-section adapted to be attached to one joint forming member so as to have a rocking movement substantially upon the apex of the angle of said strip relative to the joint forming member to which it is attached, and to be engaged first at one of the free ends of said angle by the oppo-

site of said joint members when the joint is closed due to the rocking movement of said strip upon the apex of said angle and ultimately engaged by both of the free ends of said angle due to said rocking movement of the strip.

3. A weatherstrip of resilient material and of angular cross-section adapted to rock substantially upon the apex of the angle of said strip with reference to one joint forming member when one section thereof is engaged by another joint forming member in the act of closing the joint to thereby form a resilient weatherstrip joint between adjacent faces of the joint forming members.

4. In combination with a frame having a polygonal opening and a closing member to close said opening, a weather-strip of resilient material and of angular cross-section adapted to have a rocking movement transversely of its length applied in sections to the joint between said opening and said closing member, said strip being rigidly attached to one of said joint forming members and in position to be engaged and rocked by the opposite of said joint forming members when said opening is closed.

5. In combination with a frame having a polygonal opening and a closing member to close said opening, a weatherstrip of resilient material and of angular cross-section adapted to have a rocking movement transversely of its length applied in sections to the straight joint sections between said opening and said closing member with interengaging ends to close the joint at the corners thereof, said strip sections being rigidly attached to one of said joint forming members in position to be engaged by the opposite joint forming member to rock said strip sections, to close both the straight sections and the respective corners of said joint.

6. A weatherstrip of resilient material and of angular cross-section adapted to be attached to one joint forming member so as to have a rocking movement relative to the joint forming member to which it is attached, and to be engaged at both of the free ends of said angle by the opposite joint member when the joint is closed due to the rocking movement of said strip.

7. A weatherstrip of resilient material and of angular cross-section adapted to be attached to one joint forming member so as to have a rocking movement relative to the joint forming member to which it is attached, and to be engaged first at one of the free ends of said angle by the opposite of said joint members when the joint is closed, and due to the rocking movement of said strip ultimately engaged by both of the free ends of the angle of said strip.

8. A weatherstrip of resilient material and of angular cross-section adapted to close

the joint across the bottom of a door by rocking substantially upon the apex of the angle of the strip with reference to one joint forming member when one section of the angle of said strip is engaged by another joint forming member in the act of closing the joint, and end sections at the ends of said strip extending substantially

in contact with the face of the joint forming member to which the strip is attached 10 and having sliding relation to said joint forming member when the strip is rocked relative thereto.

In testimony whereof I have hereunto affixed my signature.

JAMES H. FOOTE.
